(57) CLAIM

The ornamental design for a merchandising ticket, as shown and described.

DESCRIPTION

FIG. 1 is a front view of a merchandising ticket, folded along a perforation;

FIG. 2 is a left side view of the merchandising ticket; and, FIG. 3 is a perspective view, from the left side of the merchandising ticket, shown partially folded along a perforation. In the drawings, the broken lines illustrate environment and form no part of the claimed design.
